UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

ELECTROMAGNETIC SWITCHING DEVICE.

1,273,245.

Specification of Letters Patent.

Patented July 23, 1918.

Application filed September 11, 1916. Serial No. 119,477.

To all whom it may concern:

Be it known that I, ALBEN E. LUNDELL, a citizen of the United States, residing at New York, in the county of Bronx and State 5 of New York, have invented certain new and useful Improvements in Electromagnetic Switching Devices, of which the following is a full, clear, concise, and exact description.

This invention relates to electromagnetic 10 switching devices, its main object being the insurance of uniform and reliable contact engagement under varying values of operating current and with a minimum required value of holding current.

15 This invention therefore provides an electromagnetic relay which, when energized, causes a contact-carrying disk of insulating material to rotate. Upon the rotation of the disk, contact plates mounted on the disk slidably engage and disengage suitably mounted contact springs to control circuits. The contact springs may be interconnected in any 20 desired manner so that a conducting circuit may be completed or interrupted between any desired number of contact springs. A 25 retractile spring may be provided for returning the insulating disk to its normal position upon the deenergization of the electromagnet.

30 The nature of this invention will be more clearly understood by reference to the accompanying drawing wherein Figure 1 is a side elevation of an electromagnetic relay showing one embodiment of this invention; Fig. 2 is a plan of the relay; and Fig. 3 is a 35 perspective of a portion of the relay showing the armature and contact springs controlled thereby.

As shown in the drawing, the relay comprises a core 5 and a winding 6 therefor, located between spool-heads 7, 7 of insulating material. Fastened to the forward spool-head 7, by means of screws 9, 9 are two arms or supports 8, 8 extending forward 45 from the spool-head. The free ends of these arms support a shaft 11, which is pivoted between two screws 10, 10 threaded into and through the free ends of the arms 8, 8. Mounted on this shaft, which is free to turn 50 about the axis of the cone-pointed bearing screws, is a disk 12 of insulating material, to the edge of which is secured a magnetic armature 13. The disk also carries contact plates 14, 14; 15, 15; 16, 16 and 17, 17, the 55 two plates of each pair being mounted on

opposite sides of the insulating disk, the surface of the plates preferably being flush with the faces of the disk. The two contact plates of each pair may or may not be electrically connected together, depending upon 60 service requirements. Mounted on the rearward extension of the core adjacent to the outer face of the rear spool-head 7, is a contact spring clamp 18, by means of which springs 19, 19; 20, 20, 21, 21 and 22, 22, 65 insulated from each other and from the frame, are held in position, as shown. The free ends of these springs are bent toward the insulating disk 12 so that they may have sliding engagement with the contact plates 70 carried by the insulating disk.

Upon the energization of the core 5 by current in the winding 6, the armature 13 is attracted and drawn into a position adjacent to the end of the core 5, thereby rotating the 75 insulating disk 12 in the direction indicated by the arrow. The rotation of the insulating disk 12 carries the contacts 14, 14 and 16, 16 into sliding engagement with contact springs 19, 19 and 21, 21, and at the 80 same time carries contact plates 15, 15 and 17, 17 out of engagement with contact springs 20, 20 and 22, 22. Assume that the contact plates of each pair are conductively 85 connected together, contact springs 19, 19 and 21, 21 will be connected together by means of the proper respective contact plates, and the normally closed connection between contact springs 20, 20 and 22, 22 will be interrupted. Upon cessation of current flow 90 through the winding 6, spring 23 restores the armature and rotatable insulating disk to normal.

In electromagnetic relays previously used for similar service, the contact pressure between the contact springs was dependent, to a large extent, upon the value of the energizing current. In relays embodying this invention, the contact pressure between the insulating disk or the contact plates and the 95 contact springs is at all times the same, regardless of the position of the armature, and is entirely independent of the magnetizing current in the electromagnet. Another feature of importance is that the minimum 100 holding current can be considerably reduced from that previously required, since it is now necessary to hold the armature in actuated position only against the force of the retractile spring, and not against that of the 110

contact springs as well, as previously was the case. Reliability of contact is further insured by the fact that the contacting surfaces are brought into sliding engagement 5 rather than into simple pressure engagement with each other.

What is claimed is:

1. In an electromagnetic switching device, a magnetic core, an energizing winding therefor, a non-conductive oscillating disk supported on one end of said core, a plurality of contact plates mounted on said disk, an armature also mounted on said disk, and a plurality of contact springs supported upon the other end of said core, and co-operating with said contact plates.
2. In an electromagnetic switching device, a magnetic core, an energizing winding therefor, spool heads on the ends of said core, a pair of supports mounted upon one of said spool heads parallel to the axis of said core, a disk pivoted between said supports, an armature and a plurality of contacts mounted upon said disk, a plurality of co-operating contact springs supported upon said core.
3. In an electromagnetic switching device, a core, an energizing winding therefor, a non-conductive oscillating disk pivotally supported on one end and on a pivot transverse to the axis of said core, a plurality of contacts and an armature carried by said disk, a plurality of contact springs co-operating therewith extending parallel to the axis of said core, and means for supporting said contact springs on the core.
4. In an electromagnetic switching device, a core, an energizing winding therefor, a disk pivoted on one end of the core, contact plates carried by said disk, an armature mounted on the edge of said disk in operative relation to said core and serving

to oscillate said disk upon the energization of said core, means for restoring the disk to its normal position upon the deenergization 45 of the core, and a plurality of contact springs supported on the other end of said core.

5. In an electromagnetic switching device, a core, an energizing winding therefor, a disk pivotally mounted on one end of said core, contact plates and armature carried by said disk, a plurality of contact springs mounted on the other end of said core having free ends and extending parallel to the core into operative relative to contacts of said disk.

6. In an electromagnetic switching device, a core, an energizing winding therefor, a disk of insulating material mounted upon an axis perpendicular to the axis of said core, an armature and contact mounted on said disk, and a plurality of co-operating contact springs supported on said core.

7. In an electromagnetic switching device, a core, an energizing winding therefor, a disk pivotally mounted in alignment with the axis of said core, an armature and contact plates carried by said disk, and contact springs co-operating with said contact plates.

8. In an electromagnetic switching device, a core, an energizing winding for said core, a disk carrying an armature and contact plates supported in alignment with the 75 axis of said core, and a plurality of contact springs extending parallel to the axis of the core and extending beyond the end thereof into co-operative relation with said contact plates.

In witness whereof I hereunto subscribe my name this 8th day of September A. D. 1916.

ALBEN E. LUNDELL.
